UNITED STATES PATENT OFFICE.

FREDERICK SIEMENS, OF DRESDEN, SAXONY, GERMANY.

CONSTRUCTION OF LAMPS.

SPECIFICATION forming part of Letters Patent No. 241,077, dated May 3, 1881.

Application filed January 5, 1881. (No model.) Patented in Germany March 25, 1879, in Great Britain April 16, 1880, in France May 31, 1880, and in Belgium June 3, 1880.

To all whom it may concern:

Be it known that I, FREDERICK SIEMENS, a citizen of Saxony, residing at Dresden, in the Empire of Germany, have invented a new and useful Improved Construction of Lamps, (for which I have obtained a patent in Great Britain, No. 1,561, bearing date April 16, 1880,) of which the following is a specification.

My invention relates to a construction of lamps wherein the heat of the products of combustion from the flame is imparted to the air-supply or to the combustible gas, or to both, for increasing the illuminating power of the flame, by causing such products of combustion and the air or gas to pass in opposite directions through adjacent regenerative chambers or passages filled with materials offering extended surfaces for giving off and taking up heat. I construct such lamps as follows:

An annular burner, consisting, by preference, of a number of small vertical tubes rising from an annular chamber into which the combustible gas passes, has its central space formed into a regenerative chamber containing materials offering extended surfaces for taking up heat, which chamber communicates at bottom with a passage or pipe leading to a chimney, and is extended upward at top to a certain height beyond the level of the burner, such extension being, by preference, of reduced diameter. This inner chamber serves for the downward passage of the products of combustion, which pass into it from the top of the flame, at its upper end, and are drawn downward through it by the draft of the chimney, into which the products escape after imparting the greater part of their heat to the sides of the chamber and the materials contained therein. Surrounding the outside of the burner is a second chamber, open at its upper and lower ends, also containing material offering extended surfaces, which material becomes heated by conduction and radiation from the heat given off to the central chamber, and imparts such heat to the air passing upward through the chamber on its way to the flame of the burner, at or about the level of which the chamber terminates, and at which point it is, by preference, made of reduced diameter. At the upper edge of such outer chamber, as also surrounding the

extension of the inner chamber at a certain distance above the top of the burner, I prefer to provide annular notched or comb-like shields, which serve to divide the heated air-supply into a number of separate jets, that are made to impinge upon the outer and inner surfaces of the flame, thereby increasing its vividness and steadiness. As the flame of the burner is drawn inward directly over the top of the inner chamber, it is necessary to carry this up to such a height as to afford the desired length of flame. For this purpose I fit onto the upper end of such chamber, which terminates at a moderate height above the burner, a separate cylinder, by preference of fire-clay or other suitable refractory material that will readily withstand the high heat of the flame at that point, and that can be renewed when it becomes deteriorated.

I prefer to construct the filling of the regenerative chambers of lamps of the kind above referred to of a number of perforated hollow cones of metal or fire-clay placed one above the other, so that the currents of the products of combustion or the air, in passing through the perforations of each cone in succession, are effectually broken up and each particle thereof brought into intimate contact with heat-absorbing or heat-imparting surfaces.

According to one arrangement for producing the requisite downward draft in the central chamber of the above-described lamp, I connect the lower end thereof to a pipe or pipes that is or are led up to and open into a tube situated immediately above the chimney of the lamp. By this arrangement, when the lamp is first lighted the whole of the products of combustion will pass up through the chimney and impart heat to the tube above, by which means a draft will be induced in the said pipe or pipes leading from the bottom of the central chamber, and after a short interval of time this draft will be sufficiently powerful to draw the whole or a great proportion of the products of combustion downward through the chamber.

According to another arrangement, suitable more particularly where a number of burners are arranged round a central stem, the arms supporting the burners constitute the pipes for leading off the products of combustion from

the lower ends of the central regenerative chambers to a tube forming part of the central stem, and constituting a chimney of sufficient height for maintaining the requisite draft, this being in the first instance produced by the ignition of a gas-jet inside the chimney. This gas-jet may be afterward extinguished and the draft be continuously kept up by not quite extinguishing the flames of the burners when not in use.

Lamps of the above-described construction may be adapted to burn effectually and with a steady flame without the aid of a chimney-glass to the burner. For this purpose the outer regenerative chamber is made of increased vertical length, so as by the increased column of heated air passing up through it to obtain sufficient intensity of the air-current for effecting perfect combustion and steadiness of flame. In this case the upper end of the outer chamber may be closed outside the burner, the whole of the air being made to pass into an annular space inside the burner, whence it is deflected in divided jets on the flame by the before-mentioned annular notched shield or deflector. When lamps constructed as above described are used in the open air the flame may be protected against the wind by a suitable lantern, by preference of bell shape, having a wide opening at bottom.

Figures 1 to 5 of the accompanying drawings show one arrangement of my before-described improved lamp. Fig. 1 shows an elevation; Fig. 2, an enlarged vertical section on line W W, Fig. 3; Fig. 3, a vertical section on line XX, Fig. 2; Fig. 4, a section on line YY, Fig. 3; and Fig. 5 shows a section on line ZZ, Fig. 2.

a is a cylindrical chamber, into which illuminating-gas is conducted through a pipe, *a'*, which may either project from a wall or bracket or form part of a gas-pendant. In the top of the chamber is fixed a ring of small tubes, *c*, through which the gas issues in a number of small jets, thus forming an annular burner. Within the chamber *a* is formed a second chamber, *i*, having a lateral opening communicating with the flue-tube *i'*, and an upper opening concentrically within the burner *c* and communicating with the lower end of the regenerative chamber *b*. This chamber contains one or more perforated metallic cones, *d*, and has its upper end contracted somewhat, as shown, and extended a certain height above the tops of the burner-tubes *c*. Upon such upper portion is fixed the notched shield or deflector *g*, and above this is fitted a separate cylinder, *k*, by preference of fire-clay, but which may also be of other suitable heat-resisting material.

Surrounding the outside of the gas-chamber *a* is a casing, *e*, extending up to nearly the tops of the burner-tubes *c*, an annular space intervening between the two, into which are introduced one or more perforated conical frusta, *f*, and which constitutes the regenerative chamber for heating the air-supply that enters the casing at the open lower end. The upper end of the casing *e* is turned over and notched, as

shown at *h*, so as to form an outer notched air-deflector.

The flue-tube *i'* may lead to any convenient flue or passage for producing the requisite draft; but by preference it is connected, as shown at Fig. 1, to a tube, *i*, immediately above the lamp, the action of which will be presently explained.

The upper part of the casing *e* is surrounded by a gallery, *o*, carrying a lamp-glass, *n*, a metal continuation, *n'*, of which opens into the closed lower end of the tube *i*, a slide or throttle valve being provided at *n*, whereby this communication may be more or less restricted.

The action of the lamp is as follows: Illuminating-gas being admitted into the chamber *a* and the jets *c* being ignited, the lamp will first burn in the ordinary manner—that is to say, the air for supporting combustion will pass up through the frusta *f*, and being partly caused to flow to the inner side of the ring of tubes will enter into combustion with the gas, and the resulting flame will be drawn upward by the draft created by the chimney-glass. After this has continued a short time (a few seconds being sufficient) the tube *i* will have become heated, and will also have heated the tube *i'*, by conduction, to such an extent as to induce a certain current in an upward direction in the latter, and in consequence of the suction thus produced at the upper end of the cylinder *k* a portion of the heated products of combustion will be caused to pass downward from the flame through the regenerative chamber *b* and chamber *i* into the flue-tube *i'*, whence they will pass into the tube *i*. On now more or less closing the communication between the chimney-glass *n* and the tube *i* nearly the whole of the products of combustion will be caused to pass downward in the direction above indicated, and will thus impart their heat to the sides and filling of the regenerative chamber *b*. This heat will be imparted, partly by radiation and partly by conduction, to the regenerative chamber and gas-tubes *c*, and consequently, also, to the air and gas passing up through them, thus producing a greatly-intensified light by their combustion, which is still further increased by the action of the notched air-deflectors in dividing up the air-supply into a number of small currents impinging on each side of the flame.

By continuing the air-casing *e* some distance downward, as shown, and making it of heat-conducting material, a column of heated air of sufficient height will be produced therein to cause an air-current of sufficient intensity for effecting perfect combustion without the aid of the chimney-draft, so that in certain cases the lamp-glass may be dispensed with.

A small annular space is left between the cylinder *o* forming the gallery and the casing *e*, through which a small air-current passes, serving to protect the glass *n* from becoming overheated. As the flame of the lamp is drawn downward over the edge of the cylinder *k* by the down-draft it will be seen that the length of this cylinder will determine the height of the flame.

It is of the greatest importance that lamps burning on the regenerative principle should have the current of heated products of combustion passing in a downward direction centrally through the burner, while the air-supply is made to pass in an upward direction, surrounding the current of the products, according to my present invention, first, because by this arrangement the transmission of heat from the products to the air will be more perfect than with any other arrangement; and, secondly, because by this means the before-described draft of heated air to the burner independently of a chimney-draft is obtained.

The peculiar form of the regenerator-filling—namely, perforated cones or conical rings of metal or other heat-resisting material—is also of great advantage in offering extended surfaces for taking up and giving off heat in chambers that are comparatively of small height and width, and, as compared with horizontal plates, these cones not only afford greatly increased surface, but also the possibility of providing a much greater number of perforations, which is of great advantage for the perfect action of the regenerators. In small apparatus, however, the filling in for the regenerators may be dispensed with, as the surfaces of the chambers *b* and *e* will of themselves be sufficient for effecting the requisite interchange of heat. In this case it is of advantage to make the sides of the chamber *b* of corrugated or ribbed metal.

The lamp may either be suspended by the gas-supply pipe *a'* or by the flue-tubes *i'* or *i''*, or it may be supported on a stand or in any other convenient manner, and two or more may be combined as a candelabrum. The tube *i''* may either be merely continued up a sufficient height to create the requisite draft or it may be connected to a flue or passage for leading off the products of combustion; or the flue-tube *i'* may be connected directly to a chimney-flue, the tube *i''* being dispensed with.

Fig. 6 shows a vertical section, and Fig. 7 a sectional plan on line V V of Fig. 6, of a modified construction of the before-described lamp. The same parts are indicated by the same letters of reference. In this case the annular gas-chamber *a* has connected to its central opening a double flue-tube, *i'*, communicating with the regenerator *b*, for the products of combustion, which branches to either side of the lamp and is connected at top to the flue-tube *i''*. The construction and action of the lamp are otherwise the same as previously described. When two or more such lamps are used in combination as a candelabrum they may be arranged as shown in elevation at Fig. 8, where the products of combustion are caused to pass through the hollow arms *i i* to the central stem, *p*, the extension *p'* of which forms the chimney-flue for creating the requisite draft. For producing such draft in the first instance a gas-jet is provided in *p'*, which may be afterward extinguished, and the draft may be maintained while the lamps are not in use by keeping them burning with a small flame during that time.

Lamps of the above-described construction may be adapted to burn effectually and with a steady flame in the open air without the aid of a chimney-glass to the burner. For this purpose the outer regenerative chamber is made of increased vertical length, so as, by the increased column of heated air passing up through it, to obtain sufficient intensity of the air-current for effecting perfect combustion and steadiness of flame.

Figs. 9, 10, and 11 show, respectively, a vertical section, a plan, and a sectional plan on line U U of Fig. 9, of a construction of lamp in which the regenerative chamber *e* for heating the air is made of some height, and constitutes a pedestal for the lamp, and may either be filled with conical perforated rings, as before described, or with wire-gauze or other suitable material, as indicated. The upper end of the chamber may either be entirely open, as in the previous arrangement, and provided both with an inner and an outer notched shield, or the space outside the burner may be closed at *x* and the whole of the heated air be caused to pass between the burner-tubes to the inner space, *y*, whence it is caused by the notched shield *g* to impinge in divided jets upon the flame. The filling of the inner regenerative chamber, *b*, is in this case formed of perforated cones of fire-clay, *d*, formed in one with cylindrical pieces *d'*, that are separate from each other, so that they can be separately removed and renewed when defective. The lower end of the chamber *b* communicates with an underground flue, *g*, leading to a chimney-flue for producing the necessary draft.

This lamp would burn with a perfectly steady flame without a glass in a quiescent atmosphere; but when employed in the open air it should be protected from the wind or draft by a lantern, and by preference I employ for this purpose a bell-shaped glass with large opening at bottom, as shown.

The lamp-glass *r* (shown at Fig. 6) is by preference made of the inverted-bell shape shown and of opal glass, an inverted conical mirror, *s*, being fitted onto the upper edge thereof, in order to reflect laterally and downward that portion of the light which otherwise is projected upward, and is thus more or less entirely lost.

Having thus described the nature of my invention and in what manner the same is to be performed, I claim—

1. The regenerative chamber through which the products of combustion pass, the filling of which presents extended heat-absorbing surfaces, in combination with other chambers or passages through which the air and gas supply to the lamp pass, substantially as described.

2. The central regenerative chamber within the annular burner, through which the products of combustion pass downward from the flame, in combination with an annular regenerative chamber surrounding the burner, through which the air passes upward.

3. In lamps wherein the products of combustion pass downward from the flame through a

central regenerative chamber, a cylindrical extension of such chamber, constructed of fire-clay or other heat-resisting material, and projecting up beyond the burner to such a height 5 as to afford the requisite length of flame, substantially as herein described.

4. A filling for the regenerative chambers of lamps, consisting of superposed hollow perforated cones or conical rings or frusta of suitable heat-resisting material, through the perforations of which the air or gases are made to pass, to take up heat therefrom or impart heat thereto, substantially as herein described.

5. In lamps having regenerative chambers for taking up heat from the products of combustion and imparting such heat to the gas and air supply, a notched air deflector or shield, whereby the air-supply is caused to impinge divided currents against the flame at or above the level of the burner, substantially as herein described.

6. In regenerative lamps, the combination of the burner-tubes *c*, the regenerative chambers *a e*, provided with filling *d f*, the notched shield

or deflectors *g h*, and the tubular extension *k*, 25 arranged and operating as herein described with reference to Figs. 1 to 6 of the drawings.

7. In regenerative lamps, the combination of the burner-tubes *c*, regenerative chambers *a e*, tubular extension *k*, flue-pipe *i i'*, and chimney *i²*, arranged and operating as herein described with reference to Figs. 1 to 6 of the accompanying drawings.

8. In regenerative lamps, the regenerative chamber *e*, for heating the air-supply, having 35 a downward extension in order to produce an upward air-current of sufficient intensity to effect perfect combustion without the aid of a chimney-draft, substantially as herein described with reference to Figs. 1 to 5 of the 40 drawings.

In testimony whereof I have signed my name to this specification in the presence of two subscribing witnesses.

FREDERICK SIEMENS.
